Attorney.

UNITED STATES PATENT OFFICE.

GEORGE KELLY, OF CHICAGO, ILLINOIS, ASSIGNOR TO THE KELLY SCROLL SECTION MANUFACTURING COMPANY, OF SAME PLACE.

NON-CONDUCTING COVERING.

SPECIFICATION forming part of Letters Patent No. 292,818, dated January 22, 1884.

Application filed May 22, 1883. (No model.)

To all whom it may concern:

Be it known that I, GEORGE KELLY, a citizen of the United States, and a resident of Chicago, in the county of Cook and State of Illinois, have invented certain new and useful Improvements in Non-Conducting Coverings; and I do hereby declare that the following is a full, clear, and exact description of the same, reference being had to the accompanying drawings, forming a part of this specification.

My invention relates to improvements in that class of non-conducting coverings in which layers of paper are used to form the covering; and the objects of my improvement are, first, to provide an improved construction and arrangement of parts whereby such coverings can be cheaply and quickly made; second, to afford means whereby the covering can be readily applied to or removed from around the pipe, &c., and have its longitudinal joint or seam made tight. I attain such objects by the construction of parts illustrated in the accompanying drawings, in which—

Figure 1 is a perspective view, illustrating my completed covering as applied to a section of steam or other pipe. Fig. 2 is an end view, illustrating the manner in which my improved covering is formed. Fig. 3 is a detail end view, showing dead-air spaces.

The mode heretofore employed in forming non-conducting coverings of paper has been to roll the paper in a closed cylindrical shape upon a mandrel to the desired thickness, and then cut it open longitudinally, so as to permit of its being sprung open in placing it on or removing from the steam or other pipe. This mode of manufacture is not only costly, but at the same time is laborious and difficult to accomplish.

In my improvement, as illustrated in the drawings, I obviate most of the difficulties heretofore met with in the manufacture of paper coverings, and more especially the necessity of cutting or slitting the covering longitudinally.

As shown, my improved covering consists of layers a , of paper or other pliable material folded upon themselves in the flat, (see Fig. 2,) and which may be pasted together or not, as desired or found most convenient. When thus laid up to the required thickness, the section is bent into the cylindrical or other shape required. (See Fig. 1.)

a' is an overlap formed by an extension of the outer layer of paper, &c., the purpose of which is to close the joint or seam a^2 of the covering by lapping over the same, and pasted or otherwise secured in place.

When desired, the covering can be lined with a suitable incombustible lining—such, for instance, as asbestos board.

When it is desired to form "dead-air" spaces in the covering, I arrange longitudinal strips a^4 , of paper or other suitable material, between the layers a of paper forming the covering, in manner indicated in Fig. 3, by which means dead-air spaces a^5 are formed in the body of the covering.

Having thus fully described my invention, what I claim, and desire to secure by Letters Patent, is—

1. A non-conducting covering for pipes, &c., composed of layers of paper, &c., folded upon themselves in the flat, and then bent to the required shape, substantially as described.

2. A non-conducting covering for pipes, &c., composed of layers of paper, &c., folded upon themselves in the flat, then bent to the required shape, and provided with an overlap, a' , as described, and for the purpose set forth.

3. A non-conducting covering composed of layers of paper, &c., in combination with longitudinal strips a^4 , arranged, as described, to form dead-air spaces.

In testimony whereof witness my hand this 18th day of May, 1883.

GEORGE KELLY.

In presence of—

ROBERT BURNS,
JEROME THOMPSON.
